UNITED STATES PATENT OFFICE.

JOSEPH H. BRUCE, OF CHICAGO, ILLINOIS, ASSIGNOR TO THE COMBINED LIQUID TANK & FREIGHT CAR COMPANY, OF HURON, SOUTH DAKOTA, A CORPORATION OF SOUTH DAKOTA.

RAILWAY-CAR.

SPECIFICATION forming part of Letters Patent No. 773,470, dated October 25, 1904.

Application filed January 13, 1904. Serial No. 188,840. (No model.)

To all whom it may concern:

Be it known that I, JOSEPH H. BRUCE, a citizen of the United States of America, and a resident of Chicago, Cook county, Illinois, have 5 invented certain new and useful Improvements in Railway-Cars, of which the following is a specification.

This invention relates to certain improvements in railway-cars, and more particularly 10 in that class of such cars, as are primarily designed for the carriage or transportation of cattle or live stock; and the object of the invention is to provide a car of this general character of a simple and inexpensive nature which shall 15 be especially well adapted for use by reason of being adapted for use in connection with freight of various other kinds and also by reason of being provided with improved means for carrying water and supplying the same to 20 the live stock or cattle in transit, so that it is not required to stop the train when it is desired to water said stock or cattle.

The invention consists in certain novel features of the construction, combination, and 25 arrangement of the several parts of the improved stock or cattle car, whereby certain important advantages are attained and the device is rendered cheaper, simpler, and otherwise better adapted and more convenient for 30 use, all as will be hereinafter fully set forth.

The novel features of the invention will be carefully defined in the claims.

In the accompanying drawings, which serve 35 to illustrate my invention, Figure 1 is a partial side elevation, partly in section, and showing a stock or cattle car provided with my improvement. Fig. 2 is a vertical section taken through the central portion of the car at the sill and showing the arrangement of liquid- 40 carrying tanks supported in said sill. Fig. 3 is a partial end view showing certain details of the water-supplying means to be hereinafter referred to. Fig. 4 is an enlarged sectional detail view showing certain features of 45 the water-supplying means to be hereinafter referred to, and Fig. 5 is a partial plan view showing the arrangement of the detachable

pump-handle forming a part of said water-supplying means.

As seen in the views, 1 indicates the car- 50 body, which is constructed in a well-known way with slatted sides, and 2 represents the car-platform, while 3 represents a plurality of closed metal tanks supported by said platform at opposite sides thereof, as indicated in Fig. 2, said tanks having their upper parts 55 embedded in the said platform and having enlarged or deeper central portions extended down within the space below the platform and between the trucks 5 5 of the car, the end 60 portions 4 of said tanks 3 3 being made comparatively shallow, as indicated in Fig. 1, so as to be capable of being carried out to the ends of the car within the platform 2. The tank is provided with a filling-inlet 6 adjacent 65 to an end of the car, or two such inlets may be provided at opposite sides of the car and in any convenient position, and at the deeper central portion of the tanks 3 3 they are provided with outlets 6^a, as seen in Fig. 1, at which 70 outlets their contents may be withdrawn. A siphon connection is also provided to permit the contents of one tank to be withdrawn at the outlet of the other and also to permit of filling one tank with liquid through the inlet 75 of the other tank, and this siphon connection is shown in Fig. 2 and comprises a pipe 26, extended between the deeper central portions of the tanks 3 3, with an end portion extended within each tank and provided with a down- 80 wardly-bent extremity 27, opening adjacent to the bottom of the tank. By this arrangement the liquid contents of one tank will be carried through the pipe 26 into the other tank, so that both tanks may be filled or emp- 85 tied in unison and through one inlet or outlet.

At one end of the car-body 1 is extended a vertical pipe 19, as seen in Figs. 1 and 3, and this pipe has its lower end extended into the end portion 4 of one of the tanks 3 3 and is 90 carried along said horizontal end portion, as indicated in dotted lines in Fig. 1, to the deeper central part of said tank 3, where its extremity 20 is bent downward, so that the open

mouth of the pipe is adjacent to the bottom of said deeper central portion and is adapted to draw off the liquid contents of the two tanks. Being arranged in this way, it will 5 be seen that substantially the entire contents of both tanks may be withdrawn through said pipe 19.

At the end of the car and at the upper end of pipe 19 is formed a chamber 8, having a 10 double door formed of a section 9, forming a part of the car-roof and hinged thereto and adapted to be opened to afford access to said chamber, and a section 10 hinged at its upper part to the edge of section 9 and also adapted 15 to be opened, so as to afford access to said chamber at the end of the car, this section 10 being adapted to close said chamber 8 at the end of the car.

The upper end of pipe 19 is extended through 20 the floor of the chamber 8 and within said chamber communicates with the barrel 7 of a pump having a pump-rod 11, the upper end of which is provided with two circular or rounded projections or enlargements 12 12, as clearly seen 25 in Figs. 1 and 5, between which enlargements is adapted to be engaged in a detachable manner a pump-handle 17, pivoted at 18 to the wall of the chamber 8 and adapted when engaged between said enlargements 12 12 to be 30 moved pivotally in a vertical direction for the operation of the pump-rod to draw water from the tanks 3 3 through pipe 19. The enlargements 12 have, as herein shown, adjacent convex surfaces to facilitate the pivotal move- 35 ment of the handle 17, and said handle is formed at one side with laterally-directed arms 13 13, between which is a slotted passage 14 to receive the portion of the rod 11 between enlargements 12 12, the end of said 40 passage communicating with a slot 15, extended lengthwise in the handle and wherein the rod 11 is adapted to move when the handle is worked pivotally. The handle 17 is of such a length that when engaged with the rod 45 11 its extremity projects outside chamber 8, and in order to permit the said chamber to be closed it is necessary to detach the handle from rod 11. When detached from the rod 11, the handle 17 is permitted to drop to the inclined 50 position (shown in Fig. 1) to permit the chamber to be closed up. When it is desired to connect the handle with the rod 11, it is only necessary to raise the handle sufficiently to permit the portion between enlargements 12 55 12 to be engaged in passage 14, whereupon the handle is moved laterally until the rod is engaged in the longitudinal slot 15 of the handle, whereupon the pump may be operated. To detach the handle, a reverse movement of 60 the parts is employed.

From the pump-barrel 7 extends a discharge-pipe 22, the lower end of which is adapted to discharge the liquid drawn from tanks 3 3 into a trough 21, extended along one 65 side of the car between the end wall at which

the pump is located and the car-door at that side of the car-body. At the opposite side of the car-door at that side of the body is a similar tank 21^a, and upon the other side of the car a similar arrangement of troughs is pro- 70 vided which I have not shown in detail, although in Fig. 3 one of said troughs corresponding in position to the trough 21 is shown in end elevation at 21^b.

At the end of trough 21 adjacent to the car- 75 door is a downwardly-extended pipe 23, the upper end of which communicates with the trough 21 at the bottom thereof, and said pipe 23 is extended down beside the car-door to a point below the platform 2, where the pipe is 80 bent horizontally, as seen at 24, and is carried along beneath the door to the opposite side thereof, at which point it is bent upward, as seen at 25, and communicates at its upper end with the bottom of tank 21^a in a way similar 85 to that in which the opposite end has communication with trough 21. By this arrangement it will be seen that when water is supplied to trough 21 from the pipe 22 said water will also be supplied to trough 21^a by way of 90 pipe connection 23, 24, and 25, and the troughs 21 and 21^a being at the same level the water will stand at the same level in each trough. The troughs at the opposite side of the car will be similarly connected by a pipe bent around 95 the car-door at that side, so that the water supplied to those troughs will stand at the same level in each trough, and between the correspondingly-located troughs 21 and 21^b at 100 opposite sides of the said end of the car-body 100 is extended a pipe connection 28, the ends of which communicate with the bottoms of the respective troughs, so that the water supplied to trough 21 will be supplied through said pipe connection to the troughs at the other 105 side of the car-body in a way similar to that in which water is supplied to trough 21^a. By this arrangement it will be seen that water may be pumped from the tanks 3 3 to fill the troughs 21 21^a 21^b, &c., from which the stock 110 or cattle drink, and this may be accomplished by a trainman in a comparatively short time and while the train is in motion, so that it is not essential to stop the train for such purposes as filling the troughs. It will also be 115 seen that since the tanks 3 3 are below the platform they are altogether out of the way and add to the strength and stability of the structure and may be made in capacities to hold a great quantity of water sufficient to 120 supply the stock or cattle during a long trip without replenishing. In this position the tanks 3 3 are altogether out of the way of the trainmen traversing the car-roofs, and a single pumping device serves to supply all of the 125 troughs of the car to which it is applied. It will also be seen that the car may be used for liquid freight which may be contained within the tanks 3 3, so that oil or other liquids may be carried in one or both of said tanks, so that 130

the car constructed according to my invention is further adapted for use without lessening in any way its advantages as a freight or stock car. It will also be obvious from the above 5 description that the device is capable of some modification without material departure from the principles and spirit of the invention, and for this reason I do not wish to be understood as limiting myself to the precise form and arrangement of the several parts of the device 10 herein set forth.

Having thus described my invention, I claim—

1. A railway-car comprising a body having troughs and having, at one of its ends, a chamber provided with a door located at the end of the car and adapted to be opened to afford access to said chamber, a liquid-tank supported beneath the car and a pumping device located 15 in said chamber and having pipe connections with the liquid-tank and with the troughs, said pumping device comprising a pump-rod and a handle pivotally mounted in the chamber at the end of the car and having means for detachable connection with the pump-rod and adapted, when so engaged with the pump-rod, to extend with its free end outside of the chamber and when disconnected from said pump-rod being adapted to be housed within 20 the chamber to permit the door thereof to be closed.

2. A railway-car comprising a body having troughs, a platform on which the body is supported, liquid-tanks supported below the platform and extended lengthwise along opposite sides of the car, a pumping device having a pipe connection with one tank and with the troughs of the car-body and adapted for withdrawing water from said tank and supplying 35 the same to the troughs of the car-body and a siphon connection extended from one tank to the other and adapted to draw water from one tank and supply it to that tank with which the pumping device has pipe connection.

4. A railway-car comprising a body having troughs, a platform on which the body is supported, a liquid - tank supported below the platform and extended lengthwise thereof with shallow end portions extended above the 40 bolsters and a deeper central part extended down between the trucks, and a pumping device having a pipe connection with the troughs of the car-body and also having a pipe connection with the tank which extends down 50 within and along the shallow end portion of said tank and has a downwardly-bent end portion extended adjacent to the deeper central portion of the tank for withdrawing liquid

from said tank and supplying the same to the troughs of the car-body.

4. A railway-car comprising a body having a door at its side, troughs extended horizontally at opposite sides of the door and at similar levels, a liquid-tank supported beneath the car-body, a pipe connection extended across 60 the car-door and having ends communicating with the lower portions of said respective troughs and adapted to supply water from one trough to the other and a pumping device having pipe connections with said liquid-tank and also with one of the troughs and adapted, when operated, to draw water from the liquid-tank and supply the same to the said trough with which said pumping device has pipe connection.

5. A railway-car having troughs at opposite sides and at similar levels, a liquid-tank supported beneath the car, a pumping device having pipe connections with said tank and also with a trough at one side of the car and 70 adapted, when operated, to draw water from the tank and supply the same to said trough and a pipe connection extended across one end of the car and having opposite ends communicating with the lower parts of troughs 75 at opposite sides of the car and adapted to supply water from one of said troughs to the other, one of the troughs with which said last-named pipe connection has communication being the trough with which the pumping device has pipe connection.

6. A railway-car comprising a body having a door in its side, troughs extended at opposite sides of the door and at similar levels, liquid - tanks supported below the platform 95 and extended lengthwise along opposite sides of the car, a pipe connection extended across the car-door and having ends communicating with the lower portions of the respective troughs at opposite sides of said door, a pumping device having pipe connections with one of said troughs at opposite sides of the car-door and with one of said liquid-tanks beneath the car and adapted, when operated, to draw water from said liquid-tank and supply 100 the same to said trough and a siphon connection extended from one liquid-tank to the other and adapted to draw water from one tank and supply it to that tank with which the pumping device has pipe connection.

Signed at Chicago this 20th day of December, 1903.

JOSEPH H. BRUCE.
